UNITED STATES PATENT OFFICE.

ROHDE REYNOLDS, OF HOUSTON, TEXAS.

VEHICLE-SIGNAL.

1,367,989.

Specification of Letters Patent. Patented Feb. 8, 1921.

Application filed September 7, 1916. Serial No. 118,874.

To all whom it may concern:

Be it known that I, ROHDE REYNOLDS, a citizen of the United States, residing at Houston, in the county of Harris and State 5 of Texas, have invented certain new and useful Improvements in Vehicle-Signals, of which the following is a specification, reference being had to the accompanying drawings.

10 This invention relates to signals for automobiles and other vehicles and particularly to signals mounted upon the rear of a vehicle and actuated by the driver for the purpose of indicating the direction in which 15 the vehicle is about to turn or whether the vehicle is about to back, stop or slow down.

The general object of my invention is to 20 provide a very simple, easily applied and easily rotated signal of this character which 25 is so constructed that it will attract a maximum of attention from the driver of a vehicle in the rear and in which the signals will be plainly observable at night as well as by day.

25 A further object of the invention is to provide a signaling mechanism in which a plurality of signal arms or semaphores are used connected by flexible connections to 30 operating means, these connections being arranged within a flexible conduit so that the mechanism may be applied in the most convenient manner to all makes of automobiles, or in various circumstances of operation.

35 Still another object is to provide a signaling device of this character which will occupy but little space and which will not readily get out of order.

Other objects will appear in the course 40 of the following description.

My invention is illustrated in the accompanying drawings, wherein:

Figure 1 is an elevation of my signaling device applied upon an automobile;

45 Fig. 2 is a sectional view of the casing 10 showing the signal actuating members within the casing and also showing the signals;

Fig. 3 is a section on the line 3—3 of 50 Fig. 2 looking in the direction of the arrows;

Fig. 4 is a sectional view of the means for operating the various signals;

Fig. 5 is a longitudinal sectional view 55 through the casing 21 at right angles to the section in Fig. 4; and

Fig. 6 is an elevation partly in section

showing a modified form of signaling mechanism.

Referring to these drawings, 10 designates a casing which is preferably of sheet metal, 60 though it may be made of any other suitable material, the casing being open at its sides but closed at its top, the sides at the rear portion of the casing being also closed. Extending through the casing from front to 65 rear, is a shaft 11, and surrounding this shaft are a plurality of sleeves 12, these sleeves being successively shorter so that the outermost sleeve is shortest of all as illustrated clearly in Fig. 2. These sleeves 70 are rotatable upon each other and upon the central shaft which is rotatable within the casing. A suitable bearing 13 may be provided to support the several sleeves and the intermediate portion of the shaft, this bearing 75 being disposed to engage the outermost sleeve 12 and being mounted in any suitable manner upon the casing. Mounted upon these several sleeves are the corresponding pulleys or band wheels 14.

80 Mounted upon the shaft 11 is a semaphore arm 15 and mounted upon each of the sleeves 12 is a corresponding semaphore arm, all of these semaphore arms being designated 16, and all alike except as regards the signaling indicia carried thereon. These semaphores are preferably of relatively thin sheet metal such as galvanized iron and are about one and five-eighths inches wide. Normally the several semaphores 15 depend 85 vertically and are concealed from view by the front of the casing 10. One of these semaphores carries upon it the word "Stop" and another one the word "Slow," still another the word "Reverse" and the 90 remaining arms carry the words "Right" and "Left" respectively. Other words or indicia may be used however.

95 Mounted in the frame 10 disposed in the lower portion of the casing are a plurality 100 of pulleys 17 and over these pulleys pass flexible connections such as chains 18 which extend upward to the several pulleys or band wheels 14, the chains being wound upon these band wheels so that when the respective chains 18 are pulled the band wheels and the respective shafts will be rotated to raise the paddles or semaphores connected thereto into horizontal position. Connected to the rear end of the casing is 110 a nipple 19 to which in turn is connected a flexible conduit 20 which, as illustrated in

Fig. 1, extends to the forward end of the automobile or other vehicle and terminates in a position convenient to the driver's seat. Connected to the forward end of this flexible conduit 20 is a box or casing 21 into which these several flexible chains or wires 18 lead. Mounted to extend through the end of the casing are a plurality of operating members or pulls designated 22 each 5 of these members being hooked shape at its outer end. These pulls operate through guides 23 mounted within the box and each pull is connected to one of the flexible connections 18. The flexible connections 18 each 10 are in the form of wires where they pass through the flexible conduit 20 and pass through a suitable spreader 24 which is mounted within the casing 21. This casing 21 is preferably mounted upon the steering 15 post but it may be mounted in any other convenient position so that the driver can readily pull up on any desired actuating member 22 so as to actuate the corresponding signal.

20 Mounted upon the front face of the casing 10 is a lamp housing 25 having a pane of red glass 26 on its face which constitutes the usual tail light and also having lateral lenses 27 whereby light from the lamp contained within the housing is directed to right and left of the casing 10 and against the faces of the signal arms or semaphores, in a manner which will be obvious from Fig. 3.

25 While I have heretofore described one form of my invention it is to be understood that many changes might be made without departing from the spirit of the invention, thus in Fig. 6 I show a modification in which the pulleys 14 and 17 are dispensed with. In this case the flexible connections 18^a which lead from the casing or box 21 are connected to the depending arms or bell crank levers 26, there being one bell crank 30 lever for each signal or semaphore arm and these bell crank levers being mounted in any suitable manner as upon a shaft 27 extending across the casing 10. The signal or semaphore arms are also mounted upon a shaft 35 28 so as to rotate independent of each other and each arm is provided with an angularly bent member 29 constituting a part of the arm or extending above the pivotal axis thereof and between the horizontal arm of 40 the corresponding bell crank lever 26 and the angular member 29 leads to a flexible connection or link 30. It will now be obvious that when any one of the flexible connections 18^a are pulled the corresponding signal arm or semaphore will be raised and that when this pull is relaxed the arm will drop to its normal position. Otherwise than 45 this the construction illustrated is the same as that previously described.

50 65 The operation of this mechanism will be

obvious from the drawings and previous description. It will be seen that my device is very simple in construction and operation and that because of the flexible conduit and the flexible operating connections which 55 pass through the conduit, the signaling device may be readily applied to any vehicle and arranged in its most convenient position. No signals are normally shown but when the car is about to move to right or 60 left or to slow down, reverse or stop, the proper actuating pull 23 is drawn upward, thus causing the signal arms to move from an obscured vertical position to a displayed horizontal position. When so displayed the 65 signal arms are lighted by the lenses 27. Inasmuch as the signal arms are preferably white with red letters thereon they may be readily distinguished at night as well as in day.

Having described my invention, what I claim is:

1. A vehicle signal including a casing adapted to be attached to the rear end of the vehicle and open at its opposite sides, 90 a shaft passing through the casing from front to rear, a plurality of sleeves mounted upon the shaft for independent rotation, said sleeves being progressively shorter so that a smaller sleeve will project at both 95 ends beyond a larger sleeve, semaphore arms mounted each upon one of said sleeves, pulleys mounted each upon each one of said sleeves, and actuating connections passing over said pulleys and connected to operating means certain connections being wound upon the pulleys reversely to certain other connections, whereby certain of the arms will shift to a display position in one direction and the remainder of the arms be 100 shifted to a display position in the opposite direction.

2. The combination with a plurality of signals, of means for actuating the signals including flexible connections extending 110 therefrom, a tubular housing through which the flexible connections extend, a casing having a width greater than the diameter of the housing and into which the connections extend, a plurality of longitudinally 115 movable pulls slidably mounted within said casing and extending out therefrom, the pulls being laterally spaced from each other, and pulleys disposed at the junction of the casing with the tubular housing and 120 between which the several flexible connections pass to the corresponding pulls, said flexible connections being convergently directed from the pulls to said pulleys.

In testimony whereof I hereunto affix my 125 signature in the presence of two witnesses.

ROHDE REYNOLDS.
